US00D392665S

United States Patent [19]

Marie Mage

[11] Patent Number: Des. 392,665

[45] Date of Patent: **Mar. 24, 1998

[54] SUNGLASS

[75] Inventor: Jerome Jacques Marie Mage,
Carlsbad, Calif.

[73] Assignee: Spy Optic, Inc., Carlsbad, Calif.

[**] Term: 14 Years

[21] Appl. No.: 63,966

[22] Filed: Dec. 19, 1996

[51] LOC (6) Cl. 16-06

[52] U.S. Cl. D16/326

[58] Field of Search D16/101, 300,
D16/306, 311, 315-317, 319-329, 335;
351/41, 44, 51, 52, 158; 2/447, 448

[57] CLAIM

The ornamental design for a sunglass, as shown and described.

DESCRIPTION

FIG. 1 is a front elevational view of the sunglass of the present invention showing my new design;

FIG. 2 is a top plan view thereof; and,

FIG. 3 is a right side elevation view thereof, the side opposite being a mirror image.

The portions of the interior surfaces not shown or described of the sunglasses forms no part of the claimed design.
